JAMES B. SPENCER, OF SYRACUSE, NEW YORK, ASSIGNOR TO UNITED STATES HOFFMAN COMPANY, OF SYRACUSE, NEW YORK, A CORPORATION OF NEW YORK.

GARMENT-PRESSING MACHINE.

1,164,616.

Specification of Letters Patent. Patented Dec. 14, 1915.

Application filed June 15, 1915. Serial No. 34,131.

To all whom it may concern:

Be it known that I, JAMES B. SPENCER, a citizen of the United States of America, and resident of Syracuse, in the county of Onondaga, in the State of New York, have invented new and useful Improvements in Garment-Pressing Machines, of which the following, taken in connection with the accompanying drawings, is a full, clear, and 10 exact description.

This invention relates to certain improvements in garment pressing machines of the class set forth in my pending application, Serial No. 876,625, filed Dec. 11, 1914, except that it refers more particularly to the means for operating the movable pressing element.

Aside from counterbalancing the movable pressing element so as to open automatically, the main object is to control the movements of said element entirely by a pedal lever so that the operator's hands may be free in spreading the garment out upon the buck and adjusting the various parts there- 25 of preparatory to pressing.

Another object is to construct the operating means in such manner that it will automatically lock itself and its pressing element in pressing position.

30 A further object is to provide simple means for releasing those parts from their locked position and allow them to be restored to their open positions by the counterbalancing means.

35 A still further object is to enable the operating means for the movable pressing element to be adjusted to regulate the degree of pressure which may be applied to the garment.

40 Other objects and uses relating to specific parts of the machine will be brought out in the following description.

In the drawings Figure 1 is a side elevation, partly in section, of a garment pressing 45 machine embodying the features of my invention, the movable press head and operating means therefor being shown in their normal or open positions, while the dotted lines show the same parts in their pressing 50 positions. Fig. 2 is a horizontal sectional view taken on line 2-2, Fig. 1.

This machine comprises a main supporting frame —1— upon which is mounted a

bracket —2— and a rock arm —3— carrying the pressing elements, technically known 55 as a buck —4— and press head —5—, the rock arm —3— being journaled intermediate its ends upon an upwardly extending arm —6— of the main supporting frame and is counterbalanced by a weight —7— on its 60 rear end so as to automatically open or raise the press head from the buck and constituting a part of the operating means for the press head.

The means for forcing the press head to 65 its pressing position comprises a pedal lever of the first kind extending forwardly and rearwardly of the machine and fulcrumed at —9— to the frame —1— some distance below the table top as —10— and within 70 easy reaching distance of the foot of the operator when standing upon the floor.

The rear end or arm of the lever —8— is connected to the rear end of the rocking support —3— by means of links —11— and 75 —12— constituting a toggle, the link —12— being connected to a bolt head —13— which is adjustable in a threaded bushing —14— on the rear end of the rocking support —3— and is held in its adjusted position by a lock 80 nut —15—, this adjustment serving to regulate the degree of opening movement of the head —5— and also to permit the toggle to automatically lock itself and the press head connected thereto in their pressing positions 85 in a manner hereinafter described.

The intermediate portion of the toggle lever —11— is connected to the head —13— by links —16— and —17— constituting another toggle flexing in a direction opposite 90 to that of the links —11— and —12— and together with the last named links constitute what may be termed a lazy-tong connection between the pedal lever —8— and rocking support —3— for the press head 95 —5—.

The link —16— extends from the link —17— across and some distance to the opposite side of the link —11— and is connected by a link —18— to a lever —19— 100 which is fulcrumed at —20— to a portion of the main supporting frame —1— and has its opposite end connected by a link —21— to the front end or arm of the lever —8—.

The link —21— is extensible to adjust 105

the levers —8— and —19— in proper relation to each other, and for this purpose is composed of end and intermediate sections, the end sections being threaded to receive 5 correspondingly threaded ends of the intermediate portion, and these sections are held in their adjusted positions by lock nuts —22—.

10 The length of the toggle levers —11— and —12— is such as to cause them to be brought into substantially the same straight line, as shown by dotted lines, when the head —5— is in its pressing position upon a garment, thus bringing the flexing joint as —23— in 15 approximately a straight line drawn between the pivots as —24— and —25— on the lower end of the lever —11— and upper end of the lever —12—, respectively, to automatically lock the head —5— in its pressing position 20 against the action of a retracting spring as —26— which is connected at one end to the pedal lever —8— and has its other end attached to a lug —27— on the main supporting frame —1—.

25 The links —12— and —17— are of approximately the same length, while the portions of the levers —11— and —16— between their pivotal connections with each other and their respective links —11— and 30 —12— are of approximately the same length, and inasmuch as the upper portion of the link —11— and the link —17— travel in substantially the same plane toward each other during the pressing operation, it is 35 evident that the movement of one will be limited by the other when they come in contact, as shown by dotted lines of Fig. 1, but are so relatively arranged as to allow the flexing joint —23— connecting the toggle levers —11— and —12— to pass through 40 and slightly beyond a straight line drawn between the pivots —25— and —12— when the press head is brought to its pressing position, at which time the opposite flexing joint as —28— will be in position to form a limiting stop for the toggle joint —23— to prevent undue movement of the joint —23— beyond said straight line. It is 45 evident, however, that by adjusting the head —13— farther away from the adjacent end of the rocking support —3—, the joint —23— may be prevented from assuming a locking position, or it may be adjusted to require greater pressure upon the pedal to 50 bring it into locking position.

55 After the press head has been brought to its pressing position and locked in the manner described, it is desirable to provide means for quickly releasing the same, and 60 for this purpose, I have provided another relatively small pedal lever —29— which is fulcrumed at —30— to the front portion of the main supporting frame directly under the main lever —8— and is provided with 65 an offset pedal —31— at one side of the

main pedal as —32— of the lever —8— where it is easily available for operation at any time.

70 The inner end of this release lever —29— is weighted and arranged in such position as to lie in close proximity to the under side of the lever —8— when the latter is forced to its pressing position, as indicated by dotted lines, Fig. 1, so that by depressing its pedal —31— the inner end thereof will 75 engage and elevate the front end of the lever —8—, thereby rocking the lower end of the lever —19— forwardly from its dotted position and incidentally rocking the upper end of the lever —11— in the same direction 80 through the medium of the link —16— which is connected thereto and also to the link —18— on the lever —19—, whereupon the weight —7— assisted by the spring —26— automatically restores the press head 85 —5— and its operating mechanism to their normal positions, it being understood that the tension of the spring —26— is just sufficient to accelerate the return of the press head and is not sufficient to break the toggle lock 90 between the levers —11— and —12— when forced to their locking positions.

95 What I claim is:

1. In a garment pressing machine, in combination with a rocking support for one of the pressing elements, operating means therefor comprising a pedal lever of the first kind, toggle connections between one arm of the lever and rocking support, and connections between the other arm of the 100 lever and toggle for flexing the toggle joint.

2. In a garment pressing machine, in combination with a rocking support for one of the pressing elements, operating means therefor comprising a pedal lever of the first kind, toggle connections between one arm of the lever and rocking support, another toggle connection between the first-named toggle and rocking support, and connections between the other arm of the 110 pedal lever and second-named toggle for flexing both toggles.

3. In a garment pressing machine, in combination with a rocking support for one of the pressing elements, operating means 115 therefor comprising a pedal lever, and toggle connections between said lever and rocking support having its flexing joint movable to a position in approximately a straight line between the points of connection with 120 the lever and rocking support to automatically lock said support in its pressing position.

4. In a garment pressing machine, in combination with a rocking support for one of 125 the pressing elements, operating means therefor comprising a pedal lever, toggle connections between said lever and rocking support having its flexing joint movable to a position in approximately a straight line 130

- between the points of connection with the lever and rocking support to automatically lock said support in its pressing position, and means operable at will and acting upon the pedal lever for breaking the toggle lock.
5. In a garment pressing machine, in combination with a rocking support for one of the pressing elements, operating means therefor comprising a pedal lever, lazy-tong connections between the pedal lever and rocking support for operating the latter as the pedal is moved in one direction, said lazy-tong having means for automatically locking the support and press head carried thereby in their pressing positions.
10. In a garment pressing machine, in combination with a rocking support for one of the pressing elements, operating means therefor comprising a pedal lever, lazy-tong connections between the pedal lever and rocking support for operating the latter as the pedal is moved in one direction, said lazy-tong having means for automatically locking the support and press head carried thereby in their pressing positions, and means operable at will for flexing the locking means to permit the parts to return to their normal positions.
15. In a garment pressing machine, in combination with a movable support for one of the pressing elements, operating means therefor comprising a pedal lever, a toggle having one of its members connected to said lever and its other member adjustably connected to the support, connections be-
- tween said toggle and pedal lever for flexing the toggle to force the support and press head carried thereby to their pressing positions, and means for automatically returning said support and press head from such 40 position.
20. In a garment pressing machine, in combination with a rocking support for one of the pressing elements having counterbalancing means therefor, means for operating 45 said support against the action of the counterbalancing means comprising a head adjustably mounted on the support, lazy-tongs pivoted at one end to said head, a pedal lever connected to one of the tong members, a link connected to another one of the tong members, a lever connected to said link, and connections between the last-named lever and pedal lever.
25. In a garment pressing machine, in combination with a rocking support for one of the pressing elements, a head adjustably mounted upon the support, a pedal lever of the first kind, lazy-tongs connected at one end to said head and having one of its members connected to one of the arms of the pedal lever, and connections between another one of the tong members and other 50 arm of the pedal lever.
30. In witness whereof I have hereunto set 55 my hand this 27th day of May, 1915.
35. JAMES B. SPENCER.
